UNITED STATES PATENT OFFICE

JULES HALTENBERGER, OF INDIANAPOLIS, INDIANA, ASSIGNOR, BY MESNE ASSIGNMENTS, TO JOSEPH C. SCHAF, JR., OF INDIANAPOLIS, INDIANA

SLEEVE-VALVE ENGINE

Application filed February 14, 1927, Serial No. 167,986. Renewed June 19, 1931.

It is the object of my invention to produce an internal combustion engine in which a sleeve-valve controlling both the inlet and exhaust of a cylinder is exposed externally rather than internally to the pressures within the cylinder, and has such pressures substantially balanced throughout its circumference; in which such sleeve-valve utilizes all or substantially all of its circumference for controlling the inlet and exhaust connections to the cylinder; in which such cylinder pressure acts externally on the sleeve-valve through a single chamber extending around the sleeve-valve and communicating with the cylinder, which single chamber communicates through ports in the sleeve-valve with both the inlet and exhaust conduits at proper times in the cycle of engine operation; in which the sleeve-valve mechanism desirably involves a single sleeve controlling both inlet and exhaust by a combined axial reciprocation and circumferential oscillation, which together produce a movement in a closed curved path of any point on the sleeve-valve; in which the aforesaid single chamber surrounding the sleeve-valve is so shaped that it permits maximum freedom of flow for the gases, and also may serve as the compression space for the associated cylinder; and in which such chamber around the sleeve-valve desirably serves as the explosion chamber, to give a desirable action of flame propagation tending to reduce or avoid detonation and thus to make possible the use of higher compression.

In carrying out my invention in its preferred form, I provide an engine in which the piston travels directly against the cylinder wall, with no sleeve-valve interposed between them although the control is by a sleeve-valve; desirably locate the piston stroke so that the piston comes substantially or very close to the cylinder head; provide sleeve-valve mechanism, desirably a single sleeve-valve, apart from the cylinder and piston and arranged to control both the inlet and exhaust for the cylinder; in the preferred form of my invention locate this sleeve-valve in the cylinder head, and arrange the axis of the sleeve-valve transverse to the axis of the

cylinder, although these features are not essential to my invention in its broader aspects; provide a chamber around the sleeve-valve and communicating with the cylinder and serving as the channel for both the intake and exhaust connections of the cylinder; provide the sleeve-valve with a core having both inlet and exhaust passages, which may be connected through suitable ports in the core and in the sleeve-valve to said chamber, and therethrough to the cylinder, at the proper points in the engine cycle; provide suitable driving mechanism for moving said sleeve-valve with a combined axial reciprocation and circumferential oscillation to get such control of the inlet and exhaust connections of said chamber to the inlet and exhaust ports in the core; and desirably provide a spark plug in such chamber, most desirably on the opposite side thereof from that where it communicates with the cylinder, to make such chamber the explosion chamber of the cylinder.

My invention is applicable to engines having any number of cylinders; but as the mechanism may merely be duplicated for various cylinders of the engine, I have illustrated my invention in connection with a single engine cylinder.

The accompanying drawings illustrate my invention: Fig. 1 is a vertical section transverse to the crank-shaft through an engine embodying my invention in a preferred form; Fig. 2 is a fragmental horizontal section substantially on the line 2—2 of Fig. 1, to show a wobble-crank on the valve-operating shaft of Fig. 1; Fig. 3 is a horizontal section substantially on the lines 3—3 of Figs. 1 and 4; Fig. 4 is a fragmental vertical section substantially on the lines 4—4 of Figs. 1 and 3; and Fig. 5 is a sectional view generally similar to Fig. 1, but showing a different arrangement of the sleeve-valve drive, the sleeve-valve ports, and the core passages.

The engine may have any number of cylinders 10, in each of which there is a piston 11 connected by a connecting rod 12 to a crank of the crank-shaft 13. The cylinder and various other parts of the engine may

be kept cool in any desired way, as by providing water jackets 14 in suitable places. All these parts of the engine may be of any suitable type, and their details are not essential to my invention. However, with my invention the piston 11 travels more nearly to the top of the engine cylinder than is ordinarily the case on sleeve-valve engines, and desirably substantially to the top save for sufficient space for clearance, as the compression space is provided elsewhere than in the cylinder itself.

In the preferred form of my invention, I provide this compression space by a chamber 20 in the cylinder head 21. This is a desirable location for this compression space, although my invention is not limited to this location. The cylinder head, which is desirably detachably mounted upon the cylinder proper, has a transverse cylindrical bore in which a sleeve-valve 22 is mounted, and the chamber 20 surrounds the sleeve-valve 22 at an intermediate part of the latter's length. This sleeve-valve, like the bore in which it is mounted, has its axis transverse to the cylinder axis in the desired form of my invention, and is provided with suitable ports 23 which control the inlet and exhaust connections for the chamber 20, and consequently for the associated cylinder, as the sleeve-valve 22 moves. Thus the inlet of combustible mixture is through the ports of the sleeve-valve 22 into the chamber 20, and thence to the cylinder 10 as the piston 11 descends from its intake stroke; and the exhaust from the cylinder 10 on the exhaust stroke is from the cylinder into the same chamber 20, and thence through the ports 23 of the sleeve-valve 22 into the exhaust passages. The inlet and exhaust passages whose communication to the chamber 20 is controlled by the sleeve-valve 22 will be described more fully below.

The chamber 20 is desirably of a shape best shown in Fig. 4. It desirably completely surrounds the sleeve-valve 22; desirably opens to the associated cylinder 10 for the full diameter of such cylinder on a plane perpendicular to the axis of the sleeve-valve (as is clear from Fig. 4); is much narrower than the diameter of the cylinder in its dimension parallel to the sleeve-valve axis (Figs. 1, 3, and 5) to reduce its cubical capacity and therefore the size of the compression space which it furnishes for the cylinder, but is desirably located at the middle part of that diameter of the cylinder; and desirably has a radial dimension outward from the outside of the sleeve-valve that is nearly as large as its axial dimension to provide a passage with minimum wall-resistance to the gas flow, but that is desirably slightly less than such axial dimension so that for a given cubical capacity the axial length of such chamber may be

made longer to permit a greater axial length of the port 23 of the sleeve-valve. That is, the axial length of the chamber 20 controls the axial dimension of the ports 23 of the sleeve-valve, and to that extent controls the size of such ports; so that desirably the axial length of the chamber is made as great as possible without materially decreasing the radial dimension of the chamber 20 outward of the sleeve-valve beyond the condition of equality with the axial dimension that would give the theoretical minimum wall resistance to the flow of gases in the chamber 20. If such radial dimension is made too small, such flow of gases is hampered by the wall resistance; but a desirable compromise may be effected by slightly reducing such radial dimension from equality with the axial dimension in order that the axial dimension may be correspondingly increased to permit greater axial length of the ports 23.

The ports 23 of the sleeve-valve 22 control the connections of the chamber 20 to ports of inlet and exhaust passages provided in a stationary core 25 fitting within the sleeve-valve 22. This core 25 is directly piloted at one end by mating surfaces 26 by which it fits within one end of the cylinder-head bore receiving the sleeve-valve 22; and is piloted at the other end by a ring 27 which fits upon that end of the core and fits within the bore or an enlargement of the bore in the cylinder-head. This holds the core 25 concentric with the bore of the cylinder-head; and the sleeve-valve 22 has a sliding fit within such bore and upon such core.

The inlet and exhaust passages in the core 25 may be variously arranged. Two such arrangements are shown in Figs. 1 and 5 respectively.

In the arrangement shown in Fig. 1, the inlet passage 30 and the exhaust passage 31 of the core are both axial passages, with water jackets 32 around the exhaust passage. The inlet passage 30 opens at the right-hand end of the core (Fig. 1) into the inlet manifold 33; and the exhaust passage 31 of the core opens at the left-hand end of the core into an exhaust manifold 34. Both the inlet passage 30 and the exhaust passage 31 of the core are forked at the plane of the chamber 20, the inlet passage being forked vertically to supply upwardly and downwardly discharging inlet ports 35 and 36, and the exhaust passage being forked horizontally to be supplied by laterally opening exhaust ports 37 and 38. The four ports 35, 36, 37, and 38 are desirably arranged in the same plane transverse to the axis of the sleeve-valve, so that they are all in the plane of and desirably substantially the full axial width of the chamber 20. With this arrangement of ports 35, 36, 37, and 38, there are desirably two ports 23 in the sleeve-valve, which ports

23 are double-purpose ports co-operating at one point in the cycle with the two inlet ports 35 and 36 and at another point in the cycle with the two exhaust ports 37 and 38. The 6 various ports are properly shaped, as indicated, for quick opening and closing as the sleeve-valve 22 is moved; and such sleeve-valve is moved with a combined axial reciprocation and circumferential oscillation 10 so that each port 23 travels in a closed curved path which includes points of registry with the associated exhaust ports and inlet ports of the core at the proper times in the cycle. The drawings show the parts in the position 15 they occupy substantially at the point of explosion, with the piston at the end of its upward compression stroke.

In the arrangement shown in Fig. 5, the inlet passage 30' and the exhaust passage 20 31' are not axial passages, but are arranged one above the other, as is clear from the left-hand end of the core of Fig. 5. Both of these passages open at the left-hand end of the core, the inlet passage 30' to the inlet manifold 23', and the exhaust passage 31' to the exhaust manifold 34'. The exhaust passage 31' may be provided with water jackets 32'. The exhaust passage 31' is forked horizontally at the plane of the chamber 20, to provide two exhaust ports at opposite sides of the core, Fig. 5 showing one of these ports 37'. The two exhaust ports in this arrangement, however, are not 180° apart, as were the exhaust ports in the arrangement shown 25 in Fig. 1, but are both slightly below the horizontal, as the port 37' is shown in Fig. 5. The inlet passage 30' communicates with a downwardly directed inlet port 36', opening at the bottom between the two exhaust ports, and with one or more inlet ports 35' above the horizontal axis of the sleeve-valve. Two of the inlet ports may be paired 30 with two of the exhaust ports to be controlled by double-purpose ports 23' in the 40 associated sleeve-valve 22; and if there is an additional inlet port 35' which cannot be so paired, there may be an additional single-purpose inlet port 39 provided in the sleeve-valve for controlling that additional inlet 45 port 35' of the core. Such an additional inlet port provides the additional inlet-port area that is desirable for high-speed engines; although in many respects I prefer to have an equal number of inlet and exhaust ports, 50 as in the arrangement shown in Fig. 1.

The sleeve-valve 22 may be given its combined movement of circumferential oscillation and axial reciprocation by various devices, suitable for causing opening and closing of the exhaust ports and inlet ports of the core at the proper points in the cycle. Two such mechanisms are shown in Figs. 1 and 5 respectively. Either of these valve-driving mechanisms may be used for driving the sleeve-valve of either Fig. 1 or Fig.

5, as there is no direct dependence of either form of sleeve-valve on either specific form of valve-driving mechanism.

In the valve-driving mechanism shown in Fig. 1, there is a valve-operating shaft 45 suitably connected to the crank-shaft 13 to be driven at half crank-shaft speed. This valve-operating shaft 45 has a wobble-crank 46 for each cylinder. Each such wobble-crank 46 is a crank which has its axis non-parallel and desirably non-co-planar with the axis of the valve-operating shaft, and per se is not new with me in the present patent application. On each wobble-crank 46 is mounted a valve-connecting rod 47, 70 which at its outer end is provided with a socket 48, which receives a ball member 49 at one end of a lever 50 having a ball-and-socket fulcrum 51 at an intermediate point of its length. Such fulcrum is in a split block 52, shown as stationarily but detachably mounted in a hole 53 extending upward alongside the associated cylinder 10. The lever 50 is desirably tubular for lightness; and slidably mounted in its upper end is a 80 pin 54 carrying a ball member 55 co-operating with a socket 56 mounted on the sleeve-valve 22 at one end thereof.

In the operation of the engine, the crank-shaft 13 drives the valve-operating shaft 45 85 in the usual manner, and as such valve-operating shaft 45 rotates it moves the socket 48 and ball member 49 back and forth both transverse to the axis of such shaft 45 and along such axis, so that the ball member 49 90 travels in a closed curved path. In consequence, the ball member 55 travels in a generally corresponding closed curved path, and moves the sleeve-valve 22 correspondingly so that such sleeve-valve has a combined axial reciprocation and circumferential oscillation 95 to produce a closed-curved path of movement of each sleeve-valve port. This closed-curved path of movement carries the parts 23 of the sleeve-valve into and out of co-operation 100 with the ports of the core at the proper points of the cycle.

In the valve-driving arrangement shown in Fig. 5, there is a valve-operating shaft 60 which is shown as driven at crank-shaft speed. 115 This is connected by suitable worm-gearing 61 opposite each cylinder 10 to a shaft 62 extending parallel to that cylinder, the worm-gearing being at the lower end of such shaft and being arranged to drive the shaft 62 at 120 half crank-shaft speed. This shaft 62 is mounted in suitable bearings in a housing 63 stationarily but removably mounted in the hole 53. At its upper end, each shaft 62 is provided with an eccentrically located pin 64, 125 which carries a ball member 65 located in a socket member 66 corresponding to the socket member 56 of Fig. 1 and similarly mounted on the associated sleeve-valve 22. The ball member 65 may move axially with respect to 130

the shaft 62, either by sliding on the eccentrically located pin 64 or by having such eccentrically located pin 64 slide in the shaft-part which carries it. This drive produces a combined movement of axial reciprocation and circumferential oscillation of the sleeve-valve 22, to cause registry of the various ports at the desired points in the cycle.

The chamber 20 serves both as a compression space and as a combustion space for the associated cylinder. To this end, in the preferred form of my arrangement, I provide a spark plug 70 whose sparking points are located within the chamber 20. This spark plug desirably projects into the chamber 20 at the opposite side thereof from the cylinder 10, so that the sleeve-valve 22 and core 25 lie between the spark and the cylinder. In consequence, ignition first occurs in the upper part of the chamber 20, above the sleeve-valve 22, and the flames travel in the chamber 20 in both directions around the sleeve-valve 22 to the cylinder 10 below. This provides a most desirable flame propagation, with a reduction or substantial avoidance of detonation, making higher compression possible. It also tends to keep the piston as a whole cooler, by exposing but part of its end surface to the first burning of the gases.

In the arrangement shown in Fig. 1, the inlet port 35 of the core discharges directly upward against the spark plug. This is of advantage in maintaining the spark-plug points cool and clean.

I claim as my invention:

1. In an internal combustion engine, the combination with a cylinder, and a piston, of sleeve-valve mechanism, said engine having a chamber therein which is open to the cylinder and in which the sleeve-valve mechanism is externally exposed for substantially its entire circumference, and a core for said sleeve-valve mechanism, said core having inlet and exhaust passages, and said inlet and exhaust passages and said sleeve-valve mechanism being provided with co-operating ports by which said respective core passages may be connected to said chamber and therethrough to the cylinder as the sleeve-valve mechanism is operated.

2. In an internal combustion engine, the combination set forth in claim 1, with the addition that said sleeve-valve mechanism is a single sleeve-valve.

3. In an internal combustion engine, the combination set forth in claim 1, with the addition that said sleeve-valve mechanism is a single sleeve-valve, and means for moving said single sleeve-valve with a combined axial reciprocation and circumferential oscillation.

4. In an internal combustion engine, the combination with a cylinder, and a piston, of sleeve-valve mechanism, a cylinder head in which said sleeve-valve mechanism is slid-

ably mounted, said cylinder head being provided with a chamber which is open to the cylinder and in which the sleeve-valve mechanism is externally exposed for substantially its entire circumference, and a core for said sleeve-valve mechanism, said core having inlet and exhaust passages, and said core passages and said sleeve-valve mechanism being provided with co-operating ports which by the movement of said sleeve-valve control the connections of said chamber to the respective core passages.

5. In an internal combustion engine, the combination set forth in claim 4, with the addition that said sleeve-valve mechanism is a single-sleeve valve.

6. In an internal combustion engine, the combination set forth in claim 4, with the addition that said sleeve-valve mechanism is a single-sleeve valve, and means for operating said single-sleeve valve with a combined axial reciprocation and circumferential oscillation.

7. In an internal combustion engine, the combination set forth in claim 1, with the addition that each of said core passages has a plurality of ports circumferentially displaced from one another and jointly controlled by the movement of said sleeve-valve to provide a multiple connection between that core passage and said chamber.

8. In an internal combustion engine, the combination set forth in claim 4, with the addition that each of said core passages has a plurality of ports circumferentially displaced from one another and jointly controlled by the movement of said sleeve-valve to provide a multiple connection between that core passage and said chamber.

9. In an internal combustion engine, the combination set forth in claim 1, with the addition that each of said core passages has a plurality of ports circumferentially displaced from one another and jointly controlled by the movement of said sleeve-valve to provide a multiple connection between that core passage and said chamber, said ports for the inlet and exhaust passages being interspersed circumferentially.

10. In an internal combustion engine, the combination set forth in claim 4, with the addition that each of said core passages has a plurality of ports circumferentially displaced from one another and jointly controlled by the movement of said sleeve-valve to provide a multiple connection between that core passage and said chamber, said ports for the inlet and exhaust passages being interspersed circumferentially.

11. In an internal combustion engine, the combination set forth in claim 1, with the addition that each of said core passages has a plurality of ports circumferentially displaced from one another and jointly controlled by the movement of said sleeve-valve

to provide a multiple connection between that core passage and said chamber, and one or more of the ports of said sleeve-valve being double-purpose ports co-operating with both an inlet port and an exhaust port of the core.

5 12. In an internal combustion engine, the combination set forth in claim 4, with the addition that each of said core passages has a plurality of ports circumferentially displaced from one another and jointly controlled by the movement of said sleeve-valve to provide a multiple connection between that core passage and said chamber, and one or more of the ports of said sleeve-valve being double-purpose ports co-operating with both an inlet port and an exhaust port of the core.

10 13. In an internal combustion engine, the combination with a cylinder, and a piston, of sleeve-valve mechanism having its axis transverse to the cylinder axis, a cylinder head in which said sleeve-valve mechanism is slidably mounted, said cylinder head being provided with a chamber which is open to the cylinder and in which the sleeve-valve mechanism is externally exposed for substantially its entire circumference, and a core for said sleeve valve mechanism, said core having inlet and exhaust passages, and said core passages and said sleeve-valve mechanism being provided with co-operating ports which by the movement of said sleeve-valve control the connections of said chamber to the respective core passages.

15 14. In an internal combustion engine, the combination with a cylinder, and a piston, of sleeve-valve mechanism, said engine having a chamber therein which is open to the cylinder and in which the sleeve-valve mechanism is externally exposed for substantially its entire circumference, said sleeve-valve mechanism having its axis transverse to the direction in which said chamber opens to the cylinder, and a core for said sleeve-valve mechanism, said core having inlet and exhaust passages, and said inlet and exhaust passages and said sleeve-valve mechanism being provided with co-operating ports by which said respective core passages may be connected to said chamber and therethrough to the cylinder as the sleeve-valve mechanism is operated.

20 15. In an internal combustion engine, the combination with a cylinder, and a piston, of a single sleeve-valve having a combined axial reciprocation and circumferential oscillation and constantly externally exposed to the pressure of the cylinder, and a core for said sleeve-valve, said core having inlet and exhaust passages whose connections to the cylinder are controlled by said single-sleeve-valve.

25 16. In an internal combustion engine, the combination with a cylinder, and a piston, of a single sleeve-valve having a combined axial reciprocation and circumferential os-

cillation and constantly externally exposed to the pressure of the cylinder, a core for said sleeve-valve, said core having inlet and exhaust passages whose connections to the cylinder are controlled by said single-sleeve-valve, and a cylinder head in which said single-sleeve-valve is mounted.

30 17. In an internal combustion engine, the combination with a cylinder, and a piston, of a single sleeve-valve having a combined axial reciprocation and circumferential oscillation and constantly externally exposed to the pressure of the cylinder, a core for said sleeve-valve, said core having inlet and exhaust passages whose connections to the cylinder are controlled by said single-sleeve-valve, and a cylinder head in which said single-sleeve-valve is mounted with its axis transverse to the cylinder axis.

35 18. In an internal combustion engine, the combination with a cylinder, and a piston, of a single sleeve-valve having a combined axial reciprocation and circumferential oscillation, a detachable cylinder head in which said single-sleeve valve is mounted, and a stationary core for said sleeve-valve, said core having inlet and exhaust passages whose connections to said cylinder are controlled by said single-sleeve valve.

40 19. In an internal combustion engine, a cylinder having a head, a piston reciprocable in said cylinder, said head being provided with a combustion chamber which communicates with the interior of the cylinder through an opening located centrally of the cylinder and having a width less than one-half the diameter of the cylinder, so that only a portion of the head of said piston will be exposed to the first-burning gas flames, the head of said piston having a substantially plane upper surface which closely approaches the combustion-chamber opening when the piston is at the end of its stroke.

45 20. The invention set forth in claim 1 with the addition that said sleeve-valve mechanism is a single sleeve-valve and that said core is normally stationary in the operation of the engine, and means for moving said single sleeve-valve with a movement having an axial component.

50 21. In an internal combustion engine, the combination with a cylinder, and a piston, of sleeve-valve mechanism, said cylinder having a pocket therein, said sleeve-valve mechanism extending through said pocket and being smaller than said pocket to provide an annular combustion chamber defined internally by the outer surface of the sleeve-valve mechanism, said annular combustion chamber being open to the cylinder at one side, a core for said sleeve-valve mechanism, said core having a gas passage, said gas passage and said sleeve-valve mechanism being provided with co-operating ports by which the gas passage may be connected to the combus-

tion chamber and therethrough to the cylinder as the sleeve-valve mechanism is operated, and a spark-plug located in said combustion chamber opposite the opening 5 through which such chamber communicates with the cylinder.

In witness whereof, I have hereunto set my hand at Indianapolis, Indiana, this 12th day of February, A. D. one thousand nine hundred and twenty-seven.

JULES HALTENBERGER.
